UNITED STATES PATENT OFFICE.

KARL PROCHASKA, OF VIENNA, AUSTRIA-HUNGARY.

DESIGN FOR A POT AND COVER LIFTER.

46,183.

Specification for Design.

Patented July 28, 1914.

Application filed May 8, 1914. Serial No. 837,341. Term of patent 14 years.

To all whom it may concern:

Be it known that I, KARL PROCHASKA, a subject of the Emperor of Austria-Hungary, residing at Vienna, Austria-Hungary, have invented a new, original, and ornamental Design for Pot and Cover Lifters, of which the following is a specification, reference being had to the accompanying drawings, forming part thereof.

Figure 1 is a perspective view of a pot

and cover lifter; Fig. 2 is a plan view; and Fig. 3 is an edge view, showing my new design.

I claim:

The ornamental design for a pot and cover lifter, as shown.

KARL PROCHASKA.
